UNITED STATES PATENT OFFICE.

AUGUSTUS H. BUTTLES, OF MILWAUKEE, WISCONSIN, ASSIGNOR TO LUEDKE-SCHAEFER-BUTTLES CO., OF MILWAUKEE, WISCONSIN, A CORPORATION OF WISCONSIN.

SHOE CONSTRUCTION.

1,139,014.

Specification of Letters Patent.

Patented May 11, 1915.

Application filed October 26, 1914. Serial No. 868,607.

To all whom it may concern:

Be it known that I, AUGUSTUS H. BUTTLES, a citizen of the United States, and resident of Milwaukee, in the county of Milwaukee and State of Wisconsin, have invented new and useful Improvements in Shoe Construction, of which the following is a description, reference being had to the accompanying drawings, which are a part 10 of this specification.

This invention relates to improvements in shoe construction.

In the manufacture of shoes the cost is materially increased by the use of leather 15 for the different inner and outer soles of the shoes and it is the ordinary practice to form the inner soles of the poorest and cheapest grades of leather in order to lessen the expense. As the poorer grades of 20 leather lack firmness and readily absorb moisture the soles of the shoes thus constructed become soggy and the stitched threads passing through said soles soon rot and break. Furthermore the inner soles of 25 the shoes retain the moisture for comparatively a long time and consequently are unsanitary and do not conduce to the good health of the wearer.

It is one of the objects of the present invention to overcome the before-mentioned 30 objectionable features and provide a shoe construction in which portions of the soles of the shoes are formed of a material which is more firm and will wear better than 35 leather, is comparatively waterproof and which may be produced at a cost considerably less than the cost of leather.

A further object of the invention is to 40 provide a shoe construction in which portions or all of the soles of the shoe are formed of an inexpensive flexible material which is substantially impervious to moisture, is easily nailed and sewed and which possesses all of the desirable qualities for 45 the purpose desired of the best grades of leather.

A further object of the invention is to 50 provide a shoe construction in which the parts when attached together form a shoe well adapted to withstand hard wear and usage.

With the above and other objects in view 55 the invention consists of the improved shoe construction and its parts and combinations

as set forth in the claims, and all equivalents thereof. 55

In the accompanying drawing in which the same reference characters indicate the same parts in all of the views: Figure 1 is a side view of the improved shoe, parts 60 broken away and other parts shown in section; Fig. 2 is a transverse sectional view taken on line 2-2 of Fig. 1; and Fig. 3 is a longitudinal sectional fragmentary view of a modified form of shoe. 65

Referring to the drawing the numeral 8 indicates the shoe upper, 9 the sole in its entirety and 10 the heel connected thereto. The upper 8 may be of any desirable form and is connected to the sole 9 and the heel 70 10, preferably by clinch nails 11 and 12, although the upper may be sewed to the sole if so desired. 80

The sole in its entirety comprises the in sole 13, the middle sole 14, the slip sole 15, 75 the outer sole 16 and the tap sole 17 which with the exception of the top and slip soles extend the full length of the shoe. The middle, slip, outer and tap soles are sewed together, as indicated by the numeral 18, before being secured to the in sole and to the upper so that the lower edge portions of the upper may be interposed between the in sole and the middle sole and be secured by clinch nails 11 to the complete sole. 85

A sock lining 19 is placed within the shoe to cover the clenched ends of the nails and to protect the socks of the wearer therefrom.

In the principal form the middle sole, the in sole and the sock lining are formed of 90 sheet fiber which is flexible and comparatively moisture proof and possesses all of the desirable characteristics of leather for shoe soles. The fiber may be easily sewed and the stitches will be firmly held without 95 the liability of breaking through the materials. The fiber is also sufficiently tough and firm to hold nails without cracking and may be easily worked to conform to the shape desired, and when shaped will hold 100 its form without warping.

Fiber costs less than one fourth the amount of the low grade leather used for the same purpose and from actual tests made stands more wear and hard usage and 105 keeps comparatively dry and is therefore better adapted for inner sole use than the leather now ordinarily used. The lower lift

20 of the heel 10 is also formed of fiber as it has been found to wear very satisfactory and is less costly than the grade of leather used for this purpose.

5 In the modified form shown in Fig. 3 the tap sole, the outer sole and the slip sole as well as the middle sole, the in sole and the sock lining are also formed of fiber. The 10 last mentioned construction is particularly adapted for shoes subjected to very hard usage and wear as the all fiber sole forms a very strong sole which is comparatively non flexible.

From the foregoing description it will be 15 seen that the use of fiber in the manufacture of soles for shoes provides for a considerable saving in cost and also provides shoes which will not absorb moisture and which will withstand wear as well if not better than 20 shoes of ordinary construction.

What I claim as my invention is:

1. A shoe construction, comprising an upper, and a sole connected thereto comprising an in sole, a middle sole, a slip sole and an 25 outer sole, the in sole and the middle sole being formed of fiber.

2. A shoe construction, comprising an upper, and a sole connected thereto comprising a sock lining, an in sole, a middle sole, a 30 slip sole and an outer sole, the sock lining

and the in sole and the middle sole being formed of fiber.

3. A shoe construction, comprising an upper, an in sole positioned within the upper and overlapping the lower edge portion of the upper, and an outer sole portion consisting of a plurality of sewed together thicknesses of material positioned below the insole and the overlapped portions of the upper, and means extending through the outer 40 sole portion and the in sole and the overlapped upper portion for connecting the parts together, the in sole and at least one of the thicknesses of the outer sole portion being formed of fiber. 45

4. A shoe sole consisting in part of a plurality of thicknesses of material sewed together along their edge portions, another thickness of material mounted thereon and connected to the first mentioned thicknesses 50 by nails extending through all of the thicknesses of material in a line within the line of the sewing, certain of the thicknesses of material being formed of fiber.

In testimony whereof, I affix my signature, in presence of two witnesses. 55
